TOWEL CABINET

Dan Hepner, Julius Zemmol, and Joseph Greenbaum, Detroit, Mich., assignors, by direct and mesne assignments, to Simplex Cabinet Corporation, Detroit, Mich., a corporation of Michigan

**Application March 30, 1935, Serial No. 13,890
Renewed April 17, 1939**

16 Claims (CL 312-38)

The invention relates to dispensing apparatus and it has particular relation to a towel cabinet for dispensing rolled toweling.

One object of the invention is to provide a simple and inexpensive towel cabinet for dispensing rolled toweling, which will enable promoting a more widespread use of devices of this character.

Another object of the invention is to provide a
10 towel cabinet of improved character wherein the
clean and soiled portions of the toweling are
separated and wound in compartments respec-
tively that are maintained sealed one with re-
spect to the other so as to thereby promote sani-
15 tation in connection with such devices.

Another object of the invention is to provide a towel cabinet wherein the soiled towel is wound simultaneously as the clean towel is unwound, which is so constructed and arranged that slip-
20 page is positively prevented, from which it fol-
lows that the soiled towel may constantly be wound at the same rate that the clean towel is unwound.

Another object of the invention is to provide
25 a towel cabinet wherein the clean towel roll and
the soiled towel roller may be quickly and easily
inserted and removed.

Another object of the invention is to provide a towel cabinet of such character that the roll 30 of clean toweling must be inserted in a proper and predetermined manner, or else unwinding of the toweling from the clean roll is prohibited.

Other objects of the invention will become apparent from the following specification, the drawings relating thereto, and from the claims hereinafter set forth.

For a better understanding of the invention, reference may be had to the drawings, wherein:

45 Fig. 3 is a cross-sectional view on a larger scale, taken substantially along the line 3—3 of Fig. 1.

Fig. 4 is a cross-sectional view, taken substantially along the line 4—4 of Fig. 3.

50 Figs. 5 and 6 are views similar to Fig. 4, but illustrating different positions of the latching mechanism shown.

Fig. 7 is a cross-sectional view taken substantially along the line 7-7 of Fig. 3.

55 Fig. 8 is a detail view illustrating the manner

in which the mirror is mounted in the frame on the door of the cabinet.

Fig. 9 is a view similar to Fig. 4, but illustrating a modification of the latching mechanism.

Fig. 10 is a view similar to Fig. 2, but illustrating another form of the invention particularly concerning the arrangement at the front of the cabinet.

Fig. 11 is a detail view of a guide for the edge of the towel;

Fig. 12 is a detail view of a different form of latching arrangement:

Fig. 13 is a cross-sectional view taken substantially along line 13-13 of Fig. 12.

Referring to Figs. 3 and 7, the cabinet proper comprises a pair of vertically disposed and spaced end walls 10 and 11 having outwardly directed flanges 12 and 13 along their vertical edges and similar flanges 15 and 16 along their upper and lower edges respectively. The back side of the cabinet is closed by a wall 17 partially overlapping the flanges 12 and 13 which may be spot welded thereto, as indicated at 18. As shown by Fig. 7, upper and lower walls 19 and 20 also extend between the end walls 10 and 11 and partially overlap the flanges 15 and 16 and are similarly welded to the latter. From the foregoing, it will be appreciated that the outer framework of the cabinet accordingly comprises two end walls 10 and 11 that are rigidly connected by the back wall 17 and the upper and lower walls 19 and 20, all of which are welded, or otherwise suitably secured, to similarly disposed flanges on the end walls.

The flanges 12, 13, 15 and 16 around the edges of the end walls 10 and 11, define spaces at the outer sides of the walls for receiving the projecting ends of shafts and operating apparatus hereinafter to be described, and such spaces normally are closed by similarly constructed housings or covers 22 and 23 that have flanged portions 24 telescopically receiving the flanges on the end walls and which substantially abut the ends of the back wall 17 and upper and lower walls 19 and 20. Such cover members are removable and may be fastened in place by screws or the like, but the illustrated method of removably securing them in position comprises coinciding pressed-out portions 26 on the cover flanges and end wall flanges that engage one another. It will be understood that, by exerting a pulling force on the cover members, they may be removed and that, when again applied, the flanges of the cover will ride over the pressed-out portions on the flanges of the end 55

walls until the pressed-out portions coincide, when they will move one into the other and removably lock the covers in position.

As best shown by Figs. 1 and 2, an upper, 5 horizontally swingable door 28 is provided for the cabinet, which is hinged along one side thereof as indicated at 29, and this door has inwardly directed marginal flanges 30 along all of its edges that substantially abut the upper and side edges 10 of the cabinet when the door is in its closed position. This door is provided with a mirror 31 mounted in a manner hereinafter to be described. Below the door 28, a second door 32 is provided, which is hinged at its lower edge, as indicated 15 at 33, so as to swing downwardly. The door 32 has similar marginal flanges 34 adapted to substantially abut the bottom and side edges of the cabinet. Along its upper edge an intermediate portion of the flange 34 is eliminated and in place 20 thereof an inwardly directed and somewhat deeper flange 35 is provided, which includes an upwardly bowed front portion 36 and a rearward flat portion 37. The flange 35 is disposed in a plane below the flange portions 34 at either 25 end thereof so as to provide a slot 38 through which toweling may pass to the front of the cabinet, and at opposite ends of this slot the flange portions 34 have upwardly projecting portions 39 that are disposed normally in the path of 30 movement of the lower flange 30 on the door 28, from which it follows that when the upper door is closed, it automatically holds the lower door in closed position. Preferably, the inner ends of the flanges 34 at each end of the slot 38 are 35 flanged downwardly so as to avoid sharp edges at the ends of the slot that might injure toweling passing through the slot.

Downward swinging of door 32 is limited by any suitable means but a metal strip 40 is illustrated for this purpose. This strip is pivoted to the door and slidably passes through a slot in flanges 24 and 13 on the end wall 10 and cover 23 and has a bent over end to prevent complete withdrawal of the strip. Preferably, the door 45 will be limited to an open position that is somewhat above the horizontal, so as to provide a holder for rolls of clean or soiled towel when changing the toweling in the cabinet.

The cabinet thus provided is separated into two 50 compartments by a partition 41 extending between the end walls 10 and 11 and back wall 17 and which may have flanged edges welded or otherwise secured to such walls. This partition 55 has an upper and substantially horizontal portion 42 extending frontwardly from the rear wall 17 to a point near the center of the cabinet, and then a downwardly and forwardly curved portion 43 that terminates in a straight portion 44 extending to the front edges of the end walls. 60 When the lower door 32 is closed, the straight portion 37 of the flange 35 on the upper edge of the door moves under the partition portion 44 in close relation thereto and from this, it will be apparent that with the lower door closed, the lower compartment is entirely separated from the upper compartment.

The upper compartment is adapted to receive a roll of clean toweling 47 and the toweling, as withdrawn from the roll, is first directed over 70 an idling roller 48 having short projecting ends 49 (shown by Fig. 3), which are movable in vertically disposed slots 50 in the end walls 10 and 11 that terminate at their upper ends in off-set portions 51 which are adapted to hold the idler 75 roller in an upper position during threading of

the toweling. The toweling, after passing over the idler roll 48, passes over a feed roller 53 and then outwardly over the upwardly bowed portion 36 and through the slot 38 and then downwardly along the outer side of the lower door 32. Below 5 the cabinet, the toweling depends in a loop 54 and then is directed upwardly through a slot 55 in the bottom wall 20 and over an upwardly directed projection 56 which is bent over and downwardly at its upper edge so as to avoid a 10 sharp edge engagement with the toweling. After the toweling leaves the projection 56, it is directed under a second feed roll 57 and then upon a take-up roller 58, which similarly has projecting end portions 59 that are guided in slots 60 15 that are inclined forwardly and downwardly and which terminate at their upper ends in horizontal portions 61 extending substantially to the front side of the cabinet.

For the purpose of guiding the edges of the 20 toweling as it passes to the feed roller 57 and preventing axial creeping of the toweling and thereby insuring smooth, uniform and full contact winding thereof over the feed roller, guides 61' are provided on the lower wall 20 at each side edge 25 of the toweling. These guides, as shown by Fig. 11, may comprise angular sheet metal elements having flanges 62 welded or otherwise secured to the end walls. As shown, end cover portions 63 are provided on the elements to avoid sharp edges 30 that would engage the toweling. It will be noted in Fig. 2 that the element tapers partially under the feed roller 57 so as to continue the guiding approximately to the point the toweling begins winding on the roller. 35

The feed rollers 53 and 57 have abrasive surfaces such as may be formed by covering them with sandpaper or emery cloth, so as to provide a friction surface for engaging the toweling and the ends thereof have trunnions 65 journaled in 40 the end walls 10 and 11. Beyond end wall 11 the trunnions 65 have sprocket wheels 66 and the diameter of the feed rolls and the diameter of the sprocket wheels are such that the rolls are driven at the same peripheral speed. A chain 45 67 connecting the sprocket wheels serves to drive them simultaneously.

The projection 56 serves to maintain the toweling in a flat and smooth condition and to insure that it is directed to the feed roll in this condition 50 so that it will be wound properly. It will be noted that the feed roll is close to the bottom wall 20 and this is desirable so as to substantially maintain the toweling close to the wall. Particularly this relation prevents excess forward movement of 55 the toweling under the roll such as might occur if the toweling were withdrawn rapidly by a jerk and then the feed rolls were checked suddenly by checking means to be described, in which event there would be a tendency for some of the toweling 60 to push forwardly under the feed roll.

The roll 47 is initially of such diameter that it is wedgingly supported between the idler roller 48 and rear wall 17 and is slightly above the partition portion 42. In the arrangement shown, 65 the roll engages a bead 68 on the wall 17 and normally will engage the wall below the bead. If the roll is inserted as shown, pulling of the toweling from the cabinet tends to pull the roll upwardly so as to relieve the wedging position of 70 the roll and unwinding movement of the latter is readily permitted. Continued unwinding of the roll reduces its size until it drops to partition portion 42 and finally only contacts with the latter and wall 17. It will be understood that it 75

- finally loses contact with idler 48 after it drops to the partition and it may be added that the feed roll is so positioned that the towel roll does not become supported thereby.
- 5 If the operator places the roll 47 in the cabinet in such manner that the towel would leave the upper side of the roll, pulling of the towel from the cabinet would tend to move the roll downwardly and there would be a tendency to 10 increase the wedging relation between the roll, idler and wall 17 and this tendency plus the fact that the roll would have to unwind counterclockwise, would cause the roll to bind against the lower portion of bead 68 and unwinding 15 would be practically prohibited. Thus, the roll would have to be inserted properly if the bead 68 is employed. Without the bead, the roll may be initially unwound when in either position even though the one position tends to increase the 20 wedging action, but the position shown is preferable so as to avoid any tendency of the roll when small or nearly exhausted to become jammed between the feed roll and partition portion 42.
- 25 The cabinet is loaded in the following manner: The idler roller 48 is raised until it rests in slot portions 51 and then while holding the roll or allowing it to rest on the lower and open door, the end of the towel is readily wound over 30 and under the feed roller 53. Then the idler is dropped to its operative position and the towel roll is placed in its position shown which automatically brings the towel over the idler roller. In positioning the towel roll, it may be turned to 35 take up the length between it and the idler or the towel may be pulled from under the feed roll until this length is taken up, so that finally, when the roll is placed on the idler, there is no appreciable surplus between the bottom of the roll 40 and the idler. Then sufficient towel is pulled from the cabinet to form the loop and to permit threading over the lower feed roll. Now, with the take-up roller 58 in its upper position, the operator may readily insert the end of the 45 towel through slot 55 and move it under the feed roller 57 after which the take-up roll is moved downwardly and the end of the towel is wound thereon sufficiently to insure take-up winding with the roll resting on the lower feed roller 57. During this threading of the towel, it depends downwardly over the free edge of the lower, open door, but this front portion of the towel may easily be pushed aside to permit access to the lower compartment. After threading 50 the towel, the doors are closed and then the towel descends along the outer face of the lower door.
- The idler at the lower end of the slots 50 does not actually contact with feed roll 53 as it is found this is not necessary, although actual contact would not interfere with the operation. The 55 position of the idler roller 48 results in a greater than half contact of the feed roll 53 with the towel, and this condition, in conjunction with the reverse winding around the idler roll plus the resistance to unwinding of the towel roll 47, insures such frictional engagement of the toweling with the feed roll that no slipping occurs, and when the toweling is pulled, the feed roll turns correspondingly. A similar contact of the toweling with the feed roll 57, plus the weight of the take-up roller 58, prevents slippage of the towel on such feed roll and since the take-up roll is turned by contact with the feed roll, the toweling is wound up on the take-up roll equally to its unwinding from the roll 47. It has been found

that there is no slippage on either feed roll, and, hence, once the loop is provided, it remains of constant length until the toweling is exhausted from the upper compartment. After it is exhausted from the upper compartment, the lower door 5 is opened and then the take-up roll may be removed by moving it upwardly until it is in the slot 61 and then by rocking it in the plane of the slot, the ends of the take-up roll may be removed from the slot and the roll may be removed 10 from the cabinet. It will be appreciated that during unwinding of the roll 47, the latter will tend to turn clockwise and move against the rear wall 17 of the cabinet and that it also will have to slip on the partition portion 42. In fact, it 15 will have to slip on both the partition and the rear wall once it is in contact with the latter, and these frictional resistances are helpful in preventing slipping of the toweling on the feed rollers, although it has been found that no slipping occurs even when the roll becomes small.

For obtaining an intermittent towel withdrawing operation, a push button releasing mechanism is provided, as shown by Figs. 4, 5 and 6. This mechanism includes a slide 70 on the outer 25 side of end wall 19 having an elongated opening 71 which receives a sleeve 72 on the right end trunnion 65 of the upper feed roll 53. At the outer side of the slide a washer 73 is provided on the sleeve for holding the slide adjacent the end wall 19, and outwardly of the washer, a disc 74 is secured to the trunnion so as to rotate therewith. A washer and screw 75 may be employed for holding the disc on the end of the trunnion. Preferably, that end of the shaft 30 projecting through the disc will be polygonal in shape and will fit in a similar opening in the disc so as to drive the latter, although a driving engagement between the disc and shaft may be obtained in any other suitable way.

As best shown by Fig. 5, the slide has three projections 76, 77 and 78, and it will be noted that these projections respectively have tapered faces 79, 80 and 81. A similar projection 82 is provided on the disc 74 and this projection similarly has a tapered face 83. A spring 84 normally tends to move the slide forwardly. The slide at its forward end terminates in a smaller portion 86 that slidably projects through openings 87 in the flanges 13 and 24 on the end wall 19 40 and cover 23 respectively, and it will be noted that the openings 87 are of sufficient dimensions that the slide may be dropped downwardly a slight amount. At its outer end, the portion 86 of the slide terminates in a button 90 that projects through a slightly enlarged opening in the upper door 28, so that the operator may push the button and move the slide rearwardly against the action of the spring 84. Outward movement of the slide is limited by a shoulder 91 on its upper edge that engages the flange 13 at the upper side of the opening 87. Outward movement of the slide also is prevented when the door is closed and locked by a latch arm 92 movable through a slot 93 in end wall 19 and forming a pivotal 45 portion of a lock 94 on the door 28 which may be operated by means of a key 95. With the door in its closed position and locked, the arm 92 is in front of the shoulder 91 and thus, forward movement of the slide is positively prevented 50 when the door is closed and locked. It will be appreciated, however, that the door may be unlocked and opened without disturbing the position of the slide as the shoulder 91 still will engage the flange 13 and it will be necessary to 55 70 75

push the button 90 downwardly before the slide can be released for forward projection by the spring 84. The opening in the door 28 for button 90 is sufficiently large that the door may be opened or closed whether or not the latch is in its projected position or in its inner position with the shoulder 91 engaging the flange 13, but the door cannot be locked until the button 90 is pushed inwardly so as to cause the shoulder 91 to engage the flange 13.

As the parts are related in Fig. 4, the feed roll is locked against movement because the projection 82 on the disc 74 is positioned vertically between the projections 77 and 78 and the feed roll 15 cannot be turned in either direction. When the button 90 is pushed inwardly, the projections 77 and 78 move inwardly past the projection 82 on the disc, as shown by Fig. 6, and continued movement of the slide in this direction causes the 20 tapered portion 79 of the projection 76 to engage the tapered side 83 of the projection 82 and cause the latter projection to move upwardly and, hence, the disc to turn clockwise a slight amount which is sufficient to place the projection 82 in front of the projection 77. The slide is then 25 maintained in the position shown by Fig. 6 until the towel is pulled, which causes the feed roll to rotate clockwise and, after a small amount of further turning of the feed roll, the projection 82 moves past the projection 77 and then the slide 30 is returned to its position shown by Fig. 4 by the spring 84. The feed roll and other movable parts of the mechanism may then turn as the towel is pulled until a certain amount of clean toweling 35 is withdrawn and a like amount of soiled towel is wound on the lower take-up roll, when the projection 82 again moves into a position for engagement with the projections on the slide. As the projection 82 engages the tapered face 81 on the 40 projection 78, an inward movement of the slide occurs sufficient to enable movement of the projection 82 upwardly past the projection 78 when once again it will move between the projections 77 and 78. As soon as it is vertically 45 between the projections, the spring again will move the slide outwardly until it is positioned as shown by Fig. 4 and the disc is again locked against movement in either direction. It may be mentioned that the spring 84, as well as rotary frictional contacts, normally tends to tilt the left end 50 of the slide upwardly so as to normally hold the shoulder 91 above the slots 87.

It will be noted also that the projection 76 is much longer vertically than the taper 79 and 55 has a second tapered edge 96. If the towel is pulled easily, the taper 96 ordinarily would not function, but if the operator jerks the towel hard at the end of the pull during which the lug 82 moves over the taper 81 on lug 78 and pushes 60 the slide rearwardly, there is a tendency to throw the slide rearwardly with enough force and momentum that the lug 76 tends to move farther back than necessary. The longer length of lug 76 and the taper 96 insures that lug 82 will move 65 upwardly without interference of lug 76 even though the operator jerks the towel hard at the end of the pull.

As long as the door is locked, only this intermittent movement can be obtained. Unlocking 70 of the door, however, moves the latch arm 92 out of position and then the slide can be tilted downwardly to cause the shoulder 91 to be disengaged from the flange 13 and then the spring 84 will cause the slide to move outwardly until the projections are related as shown by Fig. 5. Then

the toweling can be withdrawn freely, as there is nothing to interrupt movement of the feed roll. This condition can arise merely by unlocking the door, and it is not necessary to open the door.

The latching mechanism shown by Fig. 9 is the 5 same as described previously, excepting that, instead of a disc 74, an arm 100 is employed having the projection 82 at its outer end. This construction may be desirable in that it facilitates manufacture and reduces the cost. 10

The cabinet construction shown by Fig. 10 is somewhat similar to that shown by Fig. 2, except that a door 101, similar to door 28, is provided, which extends throughout the vertical height of the cabinet in front thereof. Thus, the lower 15 door 32, as shown by Fig. 2, is not employed. In place of this lower door, a partition door 102 is provided, which is hinged at its lower edge, as indicated at 103, and which, at its upper edge, has a flange portion 104 overlapping the front 20 edge of the partition 41. In this connection it may be noted that the toweling in being withdrawn from the cabinet, rests on and is guided over the upper edge of the lower door 32 in the construction shown by Fig. 2 and over the upper 25 edge of the partition door 102 in the construction shown by Fig. 10. In the latter construction, the toweling passes over the upper edge of the partition door 102 and then downwardly between the outer door and such partition door and is with- 30 drawn between the lower edge of the outer door and the front edge of the bottom wall 20. A slot 105 is provided between the lower edge of the door 101 and the bottom wall 20 for this purpose and the lower edge of the partition door 102 is bent 35 downwardly and rearwardly slightly so as to facilitate movement of the toweling past the lower edge of the outer door and through the slot.

Referring to Fig. 8, the mirror is mounted on the front door and its edges are disposed in a 40 frame 110 of channel shape and having a longer leg 111 and a shorter leg 112. Three sides of the frame may be assembled with the inner portion of leg spot welded to the door and then the mirror may be inserted by sliding it through the open 45 side, after which the fourth side may be applied. At the ends of the fourth side, a stepped locking junction including V-shape portions 113 and 114, is provided which positively prevents removal of the fourth side when once assembled and the 50 frame is secured against the outer face of the door. Initially, such V-shape portions are bent towards the glass slightly and then, when the fourth side is inserted, the portion 113 rides over the portion 114 and then snaps in behind the latter. Sufficient space between the glass and inner portion of leg 111 is provided for this purpose. 55

The cabinet is adapted to be hung on a wall or the like and for this purpose key hole slots 115 may be provided in the back wall 17. This manner of supporting the cabinet conceals the supporting means.

Figs. 12 and 13 illustrate another form of latching arrangement. Here, the shoulder 91 is eliminated and a U-shape element 120 has its base 65 vertically slidable in the slot 93 with one of its legs inside end wall 10 and its other leg outside the wall and between the shoulder 89 on the slide and the flange 13 on the end wall. Thus, even though the door is unlocked, the slide cannot 70 move outwardly and it is necessary to open the door and manually raise the element 120 until it is above the shoulder 89 and then the spring 84 throws the slide out. The element 120 then drops and rests on the upper edge of the projected slide, 75

but as soon as the slide is pushed inwardly, it drops in front of shoulder 89 to hold the slide against outward movement. It may be noted that the locking arm 92 also is in front of the shoulder 89 until the door is unlocked.

The invention provides a towel cabinet which is of simple construction and which can be manufactured largely from sheet metal by stamping operations. Furthermore, it provides an arrangement which enables inserting a clean roll of toweling quickly and readily and threading it past the upper feed roll as well as threading it through the bottom wall of the cabinet and over the lower feed roll and take-up roll. It will be appreciated that the clean toweling is maintained in an upper compartment which is sealed from the lower compartment and this is desirable in that it promotes sanitation by maintaining the soiled toweling separated from the clean toweling.

Moreover, the invention provides an arrangement which positively prevents slipping of the clean toweling with respect to the clean toweling feed roll and slipping between the soiled toweling and the soiled towel feed roll. Since

the feed rolls are driven at the same rate of speed, it follows that the loop of toweling initially provided will be maintained at all times until the clean toweling is exhausted from the upper compartment. In this connection, it may be pointed out that even after the clean towel roll is exhausted, withdrawal of clean toweling will still function to turn the upper feed roll until the end of the clean toweling actually leaves the idler roll 43. Thus, waste is reduced to a minimum.

The latching mechanism is of simple character and is very durable even though subjected to continuous operation over a long period of time. Furthermore, this latching mechanism provides a simple way of preventing any

reverse movement of the feed rolls such as might be occasioned by pulling the soiled toweling from the lower compartment instead of pulling the clean toweling from the upper compartment.

Threading of the toweling is a simple operation and improper application of the clean roll of toweling is positively prevented because clean toweling cannot be withdrawn unless it is properly disposed in the upper compartment.

Although more than one form of the invention has been illustrated and described in detail, it will be apparent to those skilled in the art that various modifications may be made without departing from the scope of the appended claims.

What is claimed is:

1. A device for dispensing sheet material comprising, a cabinet having a dispensing feed roller, a movable latching member having a pair of stops, a stop rotatable with the feed roller and adapted to be positioned between the pair of stops to prevent rotation of the feed roller in either direction, means for moving the latching member to allow rotation of the feed roller, and means for automatically returning the rotary stop to a position between said pair of stops, when the feed roller is operated for dispensing.

2. A device for dispensing sheet material comprising, a cabinet, a dispensing feed roller, a movable latching member having a pair of stops, a stop rotatable with the feed roller and adapted to be positioned between the pair of stops to prevent rotation of the feed roller in either direction, means for moving the latching member to allow rotation of the feed roller for dispensing, means for automatically returning the rotary stop to a position between said pair of stops after

a predetermined degree of rotation of the feed roller in dispensing direction, said last mentioned means comprising a spring for normally returning the latching member to its original position, and means on one of the latching member stops engaging the rotary stop for moving the latching member slightly against the action of the spring until said rotary stop is disposed between the pair of stops.

3. A device for dispensing sheet material comprising, a cabinet having a feed roller, means providing for successive dispensing operations of the feed roller, including a roller-latching element translatable in a direction transverse to the axis of the roller to a position wherein the roller is released for continued rotation, and a key operated lock having a latch element for normally preventing movement of the roller-latching element to such releasing position, but permitting such movement of the element when the lock is actuated by the key.

4. A device for dispensing sheet material comprising, a cabinet having a feed roller, means providing for successive dispensing operations of the feed roller, including a roller-latching element translatable in a direction transverse to the axis of the roller to a position wherein the roller is released for continued rotation, means normally urging the element to such released position, and a key-operated lock having a latch for normally preventing movement of the roller-latching element to released position, but permitting such movement of the element when the lock is actuated by the key.

5. A device for dispensing sheet material comprising, a cabinet having a feed roller, a movable latching member having first and second lugs spaced along the member and the first of which has a tapered side next to the second lug, a stop rotatable with the feed roll, and means normally urging the latching member to a position where the second lug thereon is in position to abut the stop at one circumferential side of the latter so as to prevent rotation of the feed roller in one direction, said first and second lugs being so arranged with respect to the stop that upon moving the latching member in one direction against said urging means, the second lug is first moved out of the path of movement of the stop and then the first lug through its tapered surface engages the stop and advances it circumferentially into a position circumferentially along side the second lug, whereby the stop may continue to advance when the roller is rotated.

6. A device for dispensing sheet material comprising, a cabinet having a feed roller, a movable latching member having a pair of stops, a stop rotatable with the feed roller and adapted to be positioned between the pair of stops to prevent rotation of the feed roller in either direction, means for moving the latching member to allow rotation of the feed roller for dispensing, means on the latching member for engaging the rotary stop and initially moving it circumferentially after movement of the member to release the feed roller, and means for automatically returning the rotary stop to a position between said pair of stops upon a predetermined degree of rotation of the feed roller.

7. A device for dispensing sheet material comprising, a cabinet having a feed roller having a single stop thereon, a device providing for the successive dispensing operations of said feed roller including a movable latching member hav-

ing means adapted when the member is in one position to cooperate only with said single stop for normally locking said feed roller against rotation in either direction, but allowing the roller 5 to turn in one direction when the member is moved to another position, and means for automatically urging said latching member to that position in which it interrupts the movement of the feed roller in either direction after a predetermined dispensing motion of the feed roll.

8. A device for dispensing sheet material comprising, a cabinet having a feed roller, means providing for successive dispensing operations of said roller, means providing for release of the 15 first means whereby continued operation of the feed roller may be effected, a door for the cabinet, a lock for the door, and means directly controlled by said lock for preventing said release except when the door is unlocked but independently of door opening movement.

9. A device for dispensing sheet material comprising, a cabinet having a feed roller, means providing for successive dispensing operations of said roller, means translatable in a direction 25 transverse to the axis of the roller and providing for release of the first means whereby continued withdrawal may be effected, a key-actuated lock, and means directly controlled by said lock for preventing said release except when the lock is 30 unlocked.

10. A cabinet for dispensing sheet material, having therein first means which is movable in either direction and which must move in one direction if material is to be obtained, a first stop movable by said means, a latching member, 35 means yieldably urging the member to an initial position from which it is moved to release the first stop, said member having second and third stops between which said first stop is adapted to 40 be received to prevent motion of said first means in either direction, and means by which engagement of the first stop with the second moves the member against the action of its urging means whereby to cause the first stop to be received between the second and third stops.

11. A sheet dispensing apparatus having means for controlling the amount of dispensing and which must move if dispensing is to occur, a releasable stop mechanism for said controlling 50 means, including a single stop movable with the controlling means, a movable stop-release part having first means engageable with said single stop to prevent motion of said stop in either direction, second means on said release part engageable with 55 said single stop after movement of said release part to release position and adapted to move said single stop out of stopping relation with said second means and in the same direction in which the single stop moved to arrive at stop position.

12. A cabinet for dispensing sheet material, comprising a dispensing control means, including a part which moves as dispensing occurs, a releasable stop mechanism for limiting the motion 60 of said part, including a stop-releasing element normally yieldably urged to a position at which the usual stopping operation of said stop mechanism will occur as dispensing proceeds, releas-

able means for limiting motion of said element at said position, said stop-releasing element being adapted when said limiting means is released, to be automatically yieldably urged away from said position and to a position at which the stop mechanism no longer functions, whereby the dispensing control means can be freely moved to allow servicing of the cabinet. 5

13. A cabinet for dispensing sheet material, comprising a dispensing control means, including a part which moves as dispensing occurs, a releasable stop mechanism for limiting the degree of motion of said part, including a stop-releasing element normally yieldably urged to a position at which the usual stopping operation of said stop mechanism will occur as dispensing proceeds, releasable means for limiting motion of said element at said position, said stop-releasing element being adapted when said limiting means is released, to be automatically yieldably urged away from said position and to a position at which the stop mechanism no longer functions, whereby the dispensing control means can be freely moved to allow servicing of the cabinet, the motions of said stop-releasing element being in the same direction respectively when moving toward and away from the position at which it is limited by said releasable limiting means. 10 15 20 25

14. A device for dispensing sheet material comprising, a cabinet having a feed roll, a latch having means engageable with a single stop on the roll to prevent rotation of the feed roll in either direction, and means for automatically moving said latch to cause said means to engage said single stop to prevent such rotations of said feed roll. 30 35

15. A device for dispensing sheet material comprising, a cabinet having therein a dispensing roller arranged between side walls of the cabinet, means externally of one of said side walls providing for successive operation of said dispensing roller, including a latching member manually movable in one direction from an initial position to permit operation of the roller and automatically movable in the opposite direction from said initial position to allow unlimited motion of the roller in dispensing direction, and means movable in a slot in one of said side walls for normally holding said latching member at said initial position, and movable to allow said automatic motion of the member to permit unlimited motion of the roller in dispensing direction. 40 45 50

16. A device for dispensing sheet material comprising, a cabinet having a feed roller, means providing for successive dispensing operations of the feed roller, including a roller-latching element movable to a position wherein the roller is released for continued rotation, and a key-operated lock having a latch element for normally preventing movement of the roller-latching element to such releasing position, but permitting such movement of the element when the lock is actuated by the key. 55 60 65
